G. B. WHEELER.
STARCHING MACHINE.

(Application filed Mar. 27, 1899.)

(No Model.)

UNITED STATES PATENT OFFICE.

GEORGE B. WHEELER, OF BELLows FALLS, VERMONT.

STARCHING-MACHINE.

SPECIFICATION forming part of Letters Patent No. 634,711, dated October 10, 1899.

Application filed March 27, 1899. Serial No. 710,593. (No model.)

To all whom it may concern:

Be it known that I, GEORGE B. WHEELER, of Bellows Falls, in the county of Windham and State of Vermont, have invented certain 5 new and useful Improvements in Starching-Machines, of which the following is a specification.

This invention relates to machines for starching collars and cuffs and other articles 10 of textile fabric, such articles being herein-after referred to under the name of "goods."

The invention has for its object to provide a simple and compact machine adapted to thoroughly incorporate the starch into the 15 goods during a relatively short progressive movement of the goods through the machine.

The invention consists in the improvements which I will now proceed to describe and claim.

20 Of the accompanying drawings, forming a part of this specification, Figure 1 represents an end elevation of a starching-machine embodying my invention. Fig. 2 represents a transverse vertical section of the same. Fig. 25 3 represents a section on the line 3 3 of Fig. 1. Figs. 4 and 5 represent perspective views of details. Fig. 6 represents an end view showing a modification. Fig. 7 represents another modification. Fig. 8 represents a 30 modified form of belt.

The same letters and numerals of reference indicate the same parts in all the figures.

In the drawings, *a* represents a starch-tank mounted on a suitable supporting-frame, 35 said tank surrounding by its sides, ends, and bottom a casing, forming a steam-chamber *b*, which receives steam through a pipe *b'* to keep the starch in the tank *a* suitably heated. An outlet-pipe *b''* extends from the bottom of 40 the tank *a* through the bottom of the casing and is provided with a suitable valve, so that the starch may be readily removed from the tank.

c represents the starching-cylinder, which 45 is affixed to a shaft *c'*, journaled in bearings on the supporting-frame of the machine, the cylinder being preferably composed of a body portion of perforated sheet metal and a covering of textile fabric placed upon said body 50 portion. The lower portion of the cylinder projects into the tank *a*, so that the cloth

covering of the cylinder is supplied with starch by the tank.

d d represent a series of pressure-rolls, which are located in the tank *a* below the cylinder and are therefore immersed in the starch. Said rolls are supported by a frame *e*, which is mounted to oscillate in a path concentric with the periphery of the cylinder, the rolls being arranged in a segmental series, so 60 that each roll acts on the goods passed, as hereinafter described, along the under surface of the cylinder. The frame *e* is provided with the guides *e'*, which are radially arranged relatively to the axis of the cylinder, and the rolls *d* are journaled in bearings *d'*, having stems or rods *d''*, which are movable in the guides *e'*. Springs *d'''*, interposed between the inner ends of the guides *e'*, and nuts *d''*, screwed upon the inner ends of the 70 rods *d''*, press said rods and the rolls *d* yieldingly toward the axis of the cylinder.

f represents an endless belt or apron composed of any suitable textile fabric and supported by guide-rolls *f' f'' f''' f''''*. The 75 guide-rolls *f'* and *f''* are arranged to hold the upper stretch of the belt in a curved position against that portion of the periphery of the cylinder which projects into the starch-tank, while the guide-rolls *f''' f'''' f'''* conduct the under stretch of the belt through the starch-tank, all as shown in Fig. 2. The rear guide-roll *f''* is pressed yieldingly against the cylinder or against the portion of the belt that is interposed between it and the cylinder in 80 order that the starch raised from the tank by the cylinder and belt may be squeezed out of the belt and the cover of the cylinder and caused to drop back into the tank. The said roll *f''* is supported by bearings attached to 85 arms *f''*, which are hinged at *f''* to the supporting-frame of the machine and are pressed toward the cylinder by means of weights *f''''*, mounted on arms *f'''*, affixed to the arms *f''*. It is obvious that this pressure may be applied to the arms and to the roll *f''* by springs suitably arranged instead of by the weights *f''''*, but I prefer the latter.

The frame *e* is adapted to oscillate about the shaft *c'*, the latter being the center of oscillation. The frame is provided with arms *e'' e'''*, projecting downwardly from the upper

portion of the frame and having open bearings e^3 at their lower ends formed to bear upon the shaft c' , said open bearings permitting the frame to rock freely upon the shaft c' and at the same time permitting the upper section of the frame to be raised from the shaft and from the lower section when disconnected from the latter, as hereinafter described.

Means are provided for oscillating the frame e about the shaft c' , and thus giving the rolls d a back-and-forth motion along the under side of the portion of the belt that bears upon the cylinder. The rolls are pressed yieldingly against this portion of the belt, so that they exert pressure upon the goods that pass between the cylinder and belt. This pressure is distributed by the oscillating motion of the frame and rolls, each roll being caused to move back and forth over a considerable extent of the periphery of the cylinder. The result of this action is that the starch which comes in contact with the goods is thoroughly incorporated into the meshes of the goods during their passage between the guide-rolls f' and f^2 . In this way a much more thorough saturation of the goods is secured during the short travel of the goods between the cylinder and belt than would be possible if the pressure-rolls did not have the described back-and-forth movement. The means here shown for oscillating the frame e comprise an eccentric wrist-pin h on a disk or pulley i and a pitman j , connecting said wrist-pin with an ear k on the frame e . It will be seen that the rotation of the pulley i will cause a back-and-forth movement of the pitman j and an oscillating movement of the frame e about the shaft c' .

Means are provided for rotating the cylinder c , and thus feeding the goods progressively between the cylinder and belt. The preferred means for rotating the cylinder is a connection between the frame e and the shaft c' , said connection being such that the shaft and cylinder receive a step-by-step motion when the frame e is oscillated. Said connection comprises a ratchet-wheel o , affixed to the shaft c' , and a pawl p , pivoted at p' to an ear formed on or affixed to the frame e . When the frame e is moved in the direction indicated by the arrow in Fig. 1, the pawl p engages the ratchet o and turns it, with the cylinder, in the same direction. When the frame e is moving in the opposite direction, a stop-pawl q , pivoted at q' to a fixed arm on the supporting-frame, engages the ratchet o and prevents backward rotation of the ratchet and cylinder. The progressive movement of the cylinder is imparted to the belt, so that the goods are carried forward between the cylinder and belt at a rate determined by the rate of rotation of the cylinder.

In Fig. 6 I show as the means of rotating the cylinder a gear connection between the shaft c' and the shaft t , which causes the oscillating motion of the frame. Said gear con-

nection comprises a worm u on the shaft t , a worm-gear u' , meshing with the worm u and affixed to an intermediate shaft u^2 , a beveled gear u^3 on the shaft u^2 , and a beveled gear u^4 on the shaft c' . I prefer to make the frame e in two general parts or sections 5, 6, one comprising the main portion of the frame that is located above the shaft of the cylinder, while the other comprises the main portion that is located below said shaft. The sections 5, 6 are separably connected, so that the section 5 can be removed from the section 6 and from the shaft c' , thus permitting the removal of said shaft and the cylinder for convenience in repairing, cleaning, or renewing its covering. As here shown, the section 5 is provided with slotted ears 7 at its rear portion and with slots 8 at its front portion. The ears 7 receive bolts 9, pivoted at 10 to the rear portion of the section 6, while the slots 8 receive studs 12, affixed to the front portion of the section 6. When the sections are connected, the nuts 90 13, screwed upon the bolts 9, hold the rear portions of the sections together, and the studs 12, entering the slots 8, hold the front portions of the sections together. When the nuts 13 are removed, the rear portion of the section 5 may be swung upwardly until the bearings e^3 clear the shaft c' . The slots 8 can then be removed from the studs 12. The section 6 will then rest loosely in the tank a . I do not limit myself to the details of mechanism here shown and may variously modify the same without departing from the spirit of my invention.

It is obvious that the rolls d instead of being allowed to rotate loosely may be fastened to their supports, so that they will rub against the apron without rotating, in which case they would constitute pressure-bars. I intend the term "rolls" as used herein to cover either loosely-rotating pressure-rolls or non-rotating pressure-bars.

The cylinder may be covered with a sheet or tube of cellular rubber instead of cloth, the rubber being elastic and compressible. The belt or apron may also be composed of cellular sheet-rubber, (see Fig. 8,) the cells x being open at the side of the belt next the cylinder. I prefer, however, to use both for the covering of the cylinder and as the material of the belt a comparatively loose textile fabric, such as cheese-cloth.

My invention may be embodied in a machine in which the periphery of the cylinder has a back-and-forth motion, the rolls d having no back-and-forth movement excepting on their own axes, the latter being stationary. Means for operating the cylinder in this way are shown in Fig. 7, in which w represents a ratchet-wheel affixed to the shaft c' of the cylinder. w' represents a lever fulcrumed on said shaft and having on one arm two oppositely-projecting dogs w^3 w^3 , each adapted to engage the ratchet w , the teeth of which are formed so that one dog can rotate the ratchet

in one direction and the other in the opposite direction. The other arm of the lever w' is connected by a pitman w^1 with the wrist-pin h on the disk i . The lever w' is oscillated on the shaft c' by the rotation of the disk i , and the dogs $w^2 w^3$ are thus caused to act alternately on the ratchet. The action of the dog w^3 is partly obstructed by a shield w^5 , attached to a fixed support and interposed between the dog w^3 and the ratchet. It will be seen, therefore, that when the lever w' is moving in the direction indicated by the arrow in Fig. 7 the dog w^3 engages the ratchet and moves the latter in the same direction a distance equal to the full throw of the dog. When the lever w' moves in the opposite direction, the dog w^3 is prevented from engaging the ratchet during the first part of its movement, the dog dropping into engagement with the ratchet after passing the shield and giving the ratchet a shorter movement than that given by the dog w^2 and in the opposite direction. The ratchet-wheel and the cylinder c are therefore rocked or rotated back and forth, the belt f moving back and forth with the cylinder, so that the goods between the belt and cylinder are subjected to a distributed pressure, due to the back-and-forth movement of the cylinder over the rolls, which have no back-and-forth movement excepting on their own axes, or the rolls may have a back-and-forth movement similar to that hereinbefore described, the rolls and cylinder moving simultaneously in opposite directions.

It will be seen that in the modification shown in Fig. 7, as well as in the preferred construction, the rolls d constitute a segmental or pressure member at one side of the belt, while the cylinder constitutes a continuous pressure member at the opposite side of the belt, the continuity of the cylinder enabling it to return the starched goods to the operator's station at the front of the machine, so that one operator can insert and remove the goods. By imparting a back-and-forth motion to one of said members, as described, sufficient pressure is imparted to the goods during their relatively short travel between the cylinder and belt to thoroughly incorporate the starch into the meshes of the goods and enable them to be returned to the operator by the cylinder properly starched.

Having thus explained the nature of the invention and described a way of constructing and using the same, although without attempting to set forth all of the forms in which it may be made or all of the modes of its use, I declare that what I claim is—

1. A starching-machine comprising a cylinder, a segmental series of rolls pressed simultaneously toward the periphery of the cylinder, a loose belt or apron interposed between the cylinder and rolls, means for presenting starch to the belt and cylinder, the said rolls constituting a segmental-pressure member at one side of the belt, while the cylinder constitutes a continuous-pressure mem-

ber at the opposite side of the belt, automatic mechanism for imparting a back-and-forth movement to one of said members to distribute the pressure on goods between them, and means for feeding the goods progressively between said members. 70

2. A starching-machine comprising a rotary cylinder, means for presenting starch to the cylinder, an endless belt or apron and guide-rollers therefor, arranged to hold a stretch of the belt in a curved position against a portion of the periphery of the cylinder, means for rotating the cylinder to cause a progressive movement of the goods between the cylinder and belt, a series of rolls bearing simultaneously on the under side of the curved portion of the belt so that they exert pressure simultaneously through the belt on the goods passing between the cylinder and belt, and means for reciprocating said pressure-rolls in a curved path to give each roll a back-and-forth motion on the curved portion of the belt and distribute its pressure on the belt and on the goods. 85

3. A starching-machine comprising a rotary cylinder, means for presenting starch to the cylinder, an endless belt or apron and guide-rollers therefor arranged to hold a stretch of the belt in a curved position against a portion of the periphery of the cylinder, means for rotating the cylinder to cause a progressive movement of the goods between the cylinder and belt, a frame mounted to oscillate in a path concentric with the periphery of the cylinder, means for oscillating said frame, and a series of rolls supported and reciprocated in a curved path by said frame, said rolls bearing simultaneously against the curved portion of the belt, and exerting pressure through the latter on the goods between the cylinder and belt. 95

4. A starching-machine comprising a rotary cylinder, means for presenting starch to the cylinder, an endless belt or apron, and guide-rollers therefor arranged to hold a stretch of the belt in a curved position against a portion of the periphery of the cylinder, a frame mounted to oscillate in a path concentric with the periphery of the cylinder, means for oscillating said frame, a series of rolls supported and reciprocated in a curved path by said frame, and connections between the frame and cylinder through which a progressive rotary motion is imparted to the cylinder and belt, said rolls bearing simultaneously against the curved portion of the belt and exerting pressure through the latter on the goods between the cylinder and belt. 110 115

5. A starching-machine comprising a rotary cylinder, means for presenting starch to the cylinder, an endless belt or apron, guide-rolls arranged at opposite sides of the cylinder to hold a stretch of said belt in a curved position against a portion of the periphery of the cylinder, means for yieldingly pressing the rear guide-roll against the cylinder to cause it to coöperate with the cylinder in 120 125 130

squeezing starch from the portion of the belt that rises from the tank, intermediate guide-rolls for the lower stretch of the belt, a series of pressure-rolls bearing simultaneously against the under side of the curved stretch of the belt, means for progressively rotating the cylinder to feed the goods between the belt and cylinder, and means for reciprocating said rolls in a curved path to distribute 10 their pressure on the belt and goods.

6. A starching-machine comprising a rotary cylinder, means for presenting starch to the cylinder, a frame mounted to oscillate in a path which is concentric with the periphery of the cylinder, radial guides on said frame, a series of pressure-rolls mounted in bearings which are radially movable in said guides, springs acting on said bearings to press the rolls inwardly toward the axis of the cylinder, a belt or apron movable between the cylinder and pressure-rolls and means for oscillating the frame to distribute the pressure of the rolls.

7. A starching-machine comprising a rotary cylinder, a ratchet-wheel affixed to the shaft of the cylinder, means for presenting starch to the cylinder, a belt or apron movable against a portion of the cylinder, a frame, mounted to oscillate on the said shaft, a series of rolls carried by said frame and arranged to bear simultaneously against the belt, means for oscillating the frame to give the rolls a back-and-forth motion on the belt, and a pawl carried by the frame and engaged

with the said ratchet-wheel, whereby the cylinder is given a step-by-step forward rotation.

8. A starching-machine comprising a rotary cylinder, a ratchet-wheel affixed to the shaft of the cylinder, means for presenting starch to the cylinder, a belt or apron movable against a portion of the cylinder, a frame mounted to oscillate on the said shaft, a series of rolls carried by said frame and arranged to bear simultaneously against the belt, means for oscillating the frame to give the rolls a back-and-forth motion on the belt, a pawl carried by the frame and engaged with the said ratchet-wheel whereby the cylinder is given a step-by-step forward rotation, and means for preventing the backward rotation of the cylinder.

9. A starching-machine comprising a rotary cylinder, means for presenting starch to the cylinder, a belt or apron movable against a portion of the cylinder, a frame composed of two separably-connected sections, one extending above and the other below the cylinder-shaft, a series of rolls supported by the lower section of the frame and arranged to bear simultaneously against the belt, and means for oscillating the frame.

In testimony whereof I have affixed my signature in presence of two witnesses.

GEORGE B. WHEELER.
